PROCESS FOR THE ELECTROLYTIC MANUFACTURE OF COMPOUNDS CONTAINING ACTIVE OXYGEN

No Drawing. Application filed June 4, 1927, Serial No. 196,629, and in France April 26, 1926.

The present invention relates to a process for the electrolytic manufacture of compounds containing active oxygen such as hydrogen peroxide, persulfuric acid, persulfates, percarbonates, etc.

There are known, up to date, electrolytic processes in which compounds containing active oxygen such as for instance persulfuric acid, persulfates, etc., are formed at the anode. Furthermore it is known that hydrogen peroxide can be obtained at the cathode when introducing oxygen into the cathode chamber.

Now we have found that it is possible to use in electrolytic processes simultaneously the anode and the cathode for the manufacture of compounds containing active oxygen and to produce in the anode chamber a compound of the persulfuric acid, or of the percarbonic acid, and in the cathode chamber hydrogen peroxide by introducing oxygen. Our new process offers considerable technical advantages over the processes known up to date. In particular, the double utilization of the current reduces the current required for a given quantity of active oxygen to only about half of that hitherto necessary. Obviously it follows that thereby a given apparatus can be rendered doubly efficient.

The process can be effected at ordinary or increased pressure and also in a continuous manner.

The following examples will serve to illustrate our invention:

Example 1.—In the anode chamber of an electrolytic cell, divided by a porous diaphragm, saturated ammonium sulfate is introduced, and into the cathode chamber sulfuric acid of 0.5% strength through which a vigorous stream of oxygen is passed. If electrolysis is now effected using an anode of platinum, a cathode of amalgamated gold, and an anode current density of 20 amps. per square decimeter and a cathode current density of 0.4 amps. per square decimeter, the potential amounts to 3.7 volts. Thereby ammonium persulfate is produced in the anode chamber, and hydrogen peroxide in the cathode chamber.

The efficiencies of the current are the same

in the anode or cathode chambers as in the manufacture of ammonium persulfate or hydrogen peroxide in separate apparatus, with the result that the quantity of active oxygen, which it is possible to produce in such separate apparatus, is obtained with about half the amount of current.

Example 2.—In the anode chamber of an electrolytic cell, divided by a porous diaphragm, sulfuric acid of 50% strength is introduced and in the cathode chamber sulfuric acid of 0.5% strength through which a vigorous stream of oxygen is passed. The anode consists of platinum, the cathode of amalgamated silver. If electrolysis is effected, using an anode current density of 100 amps. per square decimeter and a cathode current density of 0.6 amps. per square decimeter, there is obtained in the anode chamber persulfuric acid and in the cathode chamber hydrogen peroxide.

We wish it to be understood that one may use, instead of the compounds mentioned, the equivalents thereof so that at the cathode for instance a percarbonate or ozone is formed.

We claim:

1. A process for producing compounds containing active oxygen by electrolysis which comprises subjecting a concentrated solution of a compound capable of forming a compound of a higher degree of oxidation containing active oxygen, to anodic electrolysis, and a weaker solution of a compound having the same acid radicle as said former compound to cathodic electrolysis while passing a vigorous stream of oxygen through the catholyte.

2. A process for the electrolytic manufacture of compounds containing active oxygen comprising the electrolysis of a concentrated solution of a sulfuric acid compound in the anode chamber and of a diluted sulfuric acid solution in the cathode chamber, using an anode of platinum, a cathode of an amalgamated noble metal, an anodic current density of more than 10 amps. per square decimeter and cathodic density of less than 1 amp. per square decimeter and passing a vigorous stream of oxygen through the cathode chamber.

3. A process for the electrolytic manufacture of compounds containing active oxygen comprising the electrolysis of a saturated ammonium sulfate solution containing sulfuric acid in the anode chamber and of a diluted sulfuric acid solution of about 0.5% strength in the cathode chamber using an anode of platinum, a cathode of amalgamated gold, an anodic current density of 20 amps. per square decimeter, a cathodic current density of 0.4 amps. per square decimeter and passing a vigorous stream of oxygen through the solution contained in the cathode chamber.
